UNITED STATES PATENT OFFICE.

A. A. WILDER, OF DETROIT, MICHIGAN, ASSIGNOR TO RUFUS BROWN, OF SAME PLACE.

IMPROVED MACHINE FOR MAKING HOOPS.

Specification forming part of Letters Patent No. **38,084**, dated March 31, 1863.

To all whom it may concern:

Be it known that I, A. A. WILDER, of Detroit, in the county of Wayne and State of Michigan, have invented a new and Improved Machine for Making Hoops for Barrels, Casks, &c.; and I do hereby declare that the following is a full, clear, and exact description of the same, reference being had to the accompanying drawings, making a part of this specification, in which—

Figure 1 is a side view of my invention. Fig. 2 is also a side view of the same opposite to that shown in Fig. 1; Fig. 3, a plan or top view of the same.

Similar letters of reference indicate corresponding parts in the several figures.

This invention consists in the employment or use of two circular saws placed on one mandrel, in connection with feed-rollers and a pressure-roller and a curved plate, all arranged in such a manner that the timber from which the hoops are formed may be sawed of a uniform width throughout its entire length, and the timber then "racked" or divided into hoops, the whole work being done simultaneously or at one operation.

To enable those skilled in the art to fully understand and construct my invention, I will proceed to describe it.

A represents a framing, which may be constructed in any proper way to support the working parts of the machine; and B is a mandrel or shaft, which is placed transversely on the framing A and has two circular saws, C C, secured upon it, the space between which is equal to the desired width the hoop-timber is to be cut. On this mandrel B there is also placed a driving-pulley, D, and another smaller pulley, E. The two saws C C work or pass through two slots, a a, in a horizontal plate, F, which is secured to the framing A. This plate F has two guides, G G, attached to it, the space between which is equal to the space between the two saws C C. The form of these guides is shown clearly in Fig. 2. On the back part of the framing A there are secured vertically two metallic plates, H H, one at each side, and in these plates there are fitted six shafts, b b' c c' d d', which are arranged in pairs one over the other, as will be understood by referring to Fig. 1. On one end of the shaft d' there is placed loosely a pulley, I, which is driven from

the pulley E on the mandrel B by means of a belt, J. The pulley I is connected to the shaft d' by means of a clutch, K, which is adjusted by a lever, l, the latter extending to the front end of the machine, so as to be within reach of the operator or other attendant. (See Figs. 2 and 3.) The shaft d' also has a pinion, e, upon it, which gears into a toothed wheel, f, on the shaft c', the latter shaft also having a pinion, g, upon it, which gears into a pinion, h, on the shaft c directly above the shaft c' and from the pinion h motion is communicated to all the other shafts, b b' d, by a train of pinions, i. (See Figs. 2 and 3.)

On the shafts b b', c c', and d, at the ends opposite to those which have the pinions attached, there are placed fluted rollers j, j', k, k', and l (see Fig. 1,) and just below the fluted roller l of the shaft d there is a curved plate, M, which is attached the framing A by means of two set-screws, m m, the latter passing through two slots, n n, in a plate, o, to which the plate M is attached.

The two shafts b c have a cross-bar, N, fitted on them, in which said shafts are allowed to rotate freely, and the cross bar N is connected by a rod, O, with a lever, P, which has a weight, Q, suspended to one end of it. A lever, R, is also connected to the shaft d of the fluted roller l, and said lever also has a weight, S, suspended at its end. The bearings p of the shafts b c d in the plate n, which adjoins the fluted rollers j k l, are open at the top, so as to admit of a vertical play or movement of said shafts.

The operation is as follows: The timber or bolt T from which the hoops are made is got out in proper form beveled or tapered at one end, and "checked" or slotted, the number of slits corresponding to the number of hoops required to be racked or split from the timber. The timber or bolt T is then shoved between the two saws C C, which cut it of a uniform width, the bolt as it passes from between the saws passing between the guides G G and then between the fluted rollers j j' k k', the latter serving as feed-rollers and drawing the timber or bolt along between the saws and also forcing the former between the roller l and the curved plate M, the timber or bolt being racked or split into hoops at this point. The pressure of the roller l on the timber or bolt

is obtained by the weight *S* on lever *R* and the pressure of the rollers *j k* on the timber or bolt is obtained by the weight *Q* on lever *P*.

From the above description it will be seen that the timber or bolt is sawed of a uniform width its entire length and racked or split into hoops at one operation.

Having thus described my invention, what I claim as new, and desire to secure by Letters Patent, is—

1. The two saws *C C* and guides *G G*, in combination with the fluted feed-rollers *j j' k k'*, all arranged as and for the purpose specified.

2. The fluted racking-roller *l* and curved

plate *M*, or its equivalent, for the purpose set forth.

3. The saws *C C*, in combination with the fluted feed-rollers *j j' k k'*, racking-roller *l*, and curved plate *M*, all arranged substantially as and for the purpose specified.

4. Sawing or otherwise bringing to a uniform width hoops or timber for the same, and racking or dividing it at one operation.

A. A. WILDER.
